(57) **CLAIM**

The ornamental design for a vehicle, toy, and/or replicas thereof, as shown and described.

DESCRIPTION

FIG. 1 is a left, front perspective view of a vehicle, toy, and/or replicas thereof according to my design;

FIG. 2 is a right, rear perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

The broken lines are for illustrative purposes only and form no part of the claimed design.

1 Claim, 6 Drawing Sheets
